UNITED STATES PATENT OFFICE

2,443,354

TOY

Gladwin E. Johnson, Chicago, Ill.

Application October 29, 1946, Serial No. 706,415

2 Claims. (Cl. 46—132)

1

This invention relates to toys and games, and more particularly, to devices of this type designed for use by children of pre-school or of school age.

The primary object of the invention is to provide a device of this character which will involve the use of a degree of skill in its operation, thereby having the beneficial effect of increasing the powers of coordination of the child using the toy.

Another important object of the invention is to provide a device of this character which is adapted to serve either as a toy or game, in that one child may use it alone, or more than one child may use the device concurrently, in the latter case it being possible for the players to compete with each other.

Another important object of the invention is to provide a device of this character which can be constructed inexpensively and simply, but which will nevertheless be of strong and durable formation.

With the foregoing and other objects in view which will appear as the description proceeds, the invention consists of certain novel details of construction and combinations of parts, hereinafter more fully described and pointed out in the claims, it being understood that changes may be made in the construction and arrangement of parts without departing from the spirit of the invention as claimed.

Referring to the drawing

Figure 1 is a side elevation of the invention.

Figure 2 is a longitudinal sectional view of a climbing figure which is a part of the invention.

Figure 3 is a rear elevation of the invention, partly in section.

Figure 4 is a sectional view taken approximately on line 4—4 and looking in the direction of the arrows, with certain parts of the device cut away.

Referring to the drawing in detail, the invention embodies a base 5 of substantially rectangular proportions, on which is mounted a standard 6, preferably formed of a length of heavy wire, which is of substantially inverted U-shaped formation, having a full turn intermediate its ends, being extended horizontally from said turn, and having straight side members downwardly and slightly outwardly extended, and having its ends embedded in the base.

There is also mounted on the base 5 a length of spring steel 7 which is secured to the base intermediate the ends of the spring steel, and intermediate the embedded ends of the standard, to the base by means of screws or like secur-

2

ing means, and which is upwardly and outwardly extended from said intermediate point toward its ends, so that the spring action contained therein can be directed up each side member of the standard 6, said spring 7 being longitudinally slotted intermediate its side edges so as to permit the side members of the standards to be extended therethrough prior to being embedded in the base.

There are slidably mounted above the spring 7, on each downwardly extended side of the standard 6, figures 8 designed to represent climbing animals, which are constructed and arranged in a particular manner to be hereinafter described in detail. In addition, a bead 9 is slidably mounted on each side of the standard 6 intermediate the figures 8 and the spring 7.

The head, arms, and torso of the figure 8 form a single body, and are formed from a single piece of material, said piece of material being formed so as to provide identical sides connected at points 9' and 11, and a securing pin 10 extending between the sides at the head and serving in addition as eyes for the figure. At points 9' and 11, as is clearly shown in the drawing, the material is bent around the standard 6 and is adapted for slidable movement thereon.

The figure 8 is further formed with a leg portion 12, which is also formed from one piece of metal having identical sides and a horizontal section 13. An elongated opening 13' is provided in the horizontal section 13, through which opening the standard 6 is extended, the leg portion 12 being adapted at this point for slidable movement on the standard.

The leg portion 12 is hinged upon the body piece, by means of a coil spring 14, the rear end of which is looped around a pin 15 extending between the sides of the body portion, and the front end of which is looped through an opening 40 in the horizontal connecting parts of the leg piece, rearward of the opening through which the standard 6 is extended. In addition, there are ears 15' extending from the leg portion 12 at the upper rear corner of each side, which are bent over upon the lower member of the body portion. By means of this construction, there is imparted to the leg portion not only a hinge movement but a tension setting up a binding action between the figures and standards 6, holding the figures 8 in place on the standard 6.

In operation, a figure 8 is positioned near the bottom of the standard 6. The spring 7 is pressed downwardly at its end and released. The bead 9 is thrust upwardly by the release of the spring 55 7 which in turn thrusts the figure 8 upwardly

along the member or standard 6. The figure 8 is adapted by its construction, as hereinbefore described, to remain stationary upon the standard 6 at the point to which it is thrust by the bead 9, due to the binding action between the figure and standard 6, as described, the spring 7 is repeatedly depressed and released, the bead on each occasion thrusting the figure 8 a distance along the standard 6, regulated by the force of the spring 7 which varies according to the tension of the spring caused by depressing and releasing the opening.

By its construction and placement of the coil spring 14, the figure 8 becomes automatically released if struck with too much force by the bead 9 and falls to the bottom, requiring a new start in order to be propelled to the top of the standard 6. It will be seen that this feature of the invention permits it to be used as a game, requiring a degree of skill in thrusting the figures to the top without their falling to the bottom and requiring new starts.

What is claimed is:

1. In a toy or game, the combination with a base of an inverted U-shaped standard having its ends embedded in the base, a flat spring secured to the base intermediate the ends of said spring, said ends being upwardly and outwardly extended, said spring having longitudinal slots through which the side members of the standards

are extended, climbing figures slidably mounted on the standards, a bead intermediate each figure and the spring, said springs and beads adapted to thrust the figures along the standards when the spring is depressed and released, means for holding the figures in raised positions along the standards, and means for automatically releasing said figures and returning them to the base when subjected to excessive force by the spring.

2. In a toy or game, the combination with a base of an inverted U-shaped standard having its ends embedded in the base, a flat spring secured intermediate its ends to the base, the ends of the spring being upwardly and outwardly extended, said spring having longitudinal slots through which the side members of the standard are extended, climbing figures slidably mounted on the side members of the standard, beads intermediate the figures and the flat spring, each figure comprising a body and leg portion, the leg portion being hinged upon the body, a coil spring having one of its ends connected to the body and its opposite end connected to the leg portion, means embodied in the figures for holding the figures in raised position, and means embodied in the figures for automatically releasing said figures and permitting their return when subjected to excessive force.

GLADWIN E. JOHNSON.
